UNITED STATES PATENT OFFICE.

CONSTANT VAN SANTVOORT, OF WAUKEGAN, ILLINOIS.

GAS HEATER.

Application filed January 16, 1922. Serial No. 529,582.

To all whom it may concern:

Be it known that I, CONSTANT VAN SANTVOORT, a citizen of the United States, and a resident of Waukegan, in the county of Lake 5 and State of Illinois, have invented a new and useful Improvement in Gas Heaters, of which the following is a full, clear, and exact description.

My invention relates to improvements in 10 gas heaters, and it consists in the combinations, constructions, and arrangements herein described and claimed.

An object of my invention is to provide a gas heater in which the heated air is by- 15 passed through a plurality of radiating pipes before it is expelled into the room.

A further object of my invention is to provide a device of the type described in which the heated air is forced through the 20 sides of the device before it is expelled therefrom.

A further object of my invention is to provide a device of the type described in which the heated air first flows outwardly 25 from the center thereof, then flows upwardly along the sides thereof, and then out at the rear.

A further object of my invention is to provide a device of the type described in which 30 the air of the room is drawn by the heated pipes and is warmed thereby.

A further object of my invention is to provide a device of the type described which is simple in construction and which permits 35 the heated air to become thoroughly dried before it is expelled therefrom, thus obviating any moisture from collecting on mirrors or the like.

Other objects and advantages will appear 40 in the following specification, and the novel features of the invention will be particularly pointed out in the appended claim.

My invention is illustrated in the accompanying drawing, forming part of this application, in which—

Figure 1 is a front elevation of the device,
Figure 2 is a side elevation of the device,

Figure 3 is a section along the line 3—3 of Figure 1, and

Figure 4 is a diagrammatic view of a portion of the device.

In carrying out my invention, I provide a casing 1 which is composed of two side members 2 and 3. The side members 2 and

3 are spaced from each other by a rear wall 55 member 4 and a front wall member 5. It will be observed from Figure 3 that the wall 4 has a portion 19 thereof bent forwardly and upwardly the portion being secured to the upper edge of the wall 5 at 6 60 (see Figure 3). A curved deflector plate 7 of the shape shown in Figure 3 is secured to the walls 2 and 3 by means of rivets 8 or the like. The plate 7 is curved and has its curved surface provided with corrugations 65 9. The upper and inner edge of the plate 7 is disposed adjacent to a gas pipe 10. It will be seen that the pipe 10 is spaced away from the wall 4, thus permitting the curved bottom of the plate 7 and the rear wall 4 to 70 act as an air conveyor. The side walls 2 and 3 also carry a deflecting plate 11 which is secured to the wall 4 and terminates a spaced distance away from the wall 5. It will be seen that the forwardly bent portion of the 75 wall 4 and the deflector 11, diverge; and, that the ends of the member 11 terminate adjacent to openings 12 and 13 in the side walls 2 and 3, respectively, and the forwardly bent portion of the member 4 is disposed along the upper edge of the openings 80 12 and 13, respectively. With this construction, air is drawn into the space in front of the plate 7 and into the space between the wall 4 and the plate 7, and, when heated, 85 will flow up into the compartment formed by the wall 5 and the forwardly bent portion of the member 4, and will then flow out through the openings 12 and 13. The side walls 2 and 3 are further spaced from each 90 other by means of strips 14 and 15. The strips in turn have supporting legs 16 attached thereto.

A pair of radiator pipes 17 and 18 is carried by the walls 2 and 3, each pipe being 95 substantially elliptical in shape. These pipes are disposed in the same plane and are spaced slightly from one another. It will be seen from Figure 3 that the pipes 17 and 18 are placed above the forwardly bent portion 19 of the member 4 and are adapted to heat the air which flows between the portion 19 and the pipes 17 and 18. A heating compartment 20 is carried by the walls 2 and 3 and is triangular in cross section. The pipes 17 and 18 communicate with the compartment 20 by means of pipes 21 and 22, respectively. The side walls 2 and 3 are also 100 105

provided with openings 23 and 24 which communicate with the compartment 20. Side radiating compartments 25 and 26 are secured to the walls 2 and 3 and are divided into two prearranged air passages (see Figures 2 and 3). As shown in Figure 2, the compartment 25 has a strip 27 so disposed therein that it is adapted to convey the heated air from the opening 12 to the pipe 17 and from the pipe 18 to the opening 23. The compartment 26 is provided with a strip 28 as clearly shown in Figure 3 which is adapted to convey the air in the opening 13 to the pipe 18 and from the pipe 17 to the opening 24. The air entering the compartment 20 by means of the openings 23 and 24 is finally expelled from the device through the rear wall of the compartment 20 which has a plurality of openings 29 therein (see Figure 4). The walls 5 and 19 form a heat retaining hood.

From the foregoing description of the various parts of the device, the operation thereof may be readily understood. As heretofore stated, when the burner pipe 10 is lit, the air in the compartment formed by the wall 5 and the portion 19 becomes heated and flows through the openings 12 and 13 and into the compartments 25 and 26. It will therefore be readily apparent that cold air will be drawn into the space in front of the plate 7 and into the space between the plate 7 and the wall 4. This air in turn will be heated and will in a like manner flow through the openings 12 and 13. The air in the compartment 25 which has just entered through the opening 12 will then flow into the pipe 17 and will divide, part of it going into the compartment 20 by means of the pipe 21, and the other part going into the compartment 26 and thence into the compartment 20 by means of the opening 24. The air in the compartment 26 which has entered from the opening 13 will flow into the pipe 18 and will then divide, part thereof going directly into the compartment 20 by means of the pipe 22, and the other part flowing on through the pipe 18 into the compartment 25 and thence through the opening 24 and into the compartment 20. It will be seen from the foregoing that the heated air flows in opposite directions in the device and effectually heats the pipes 17 and 18, the compartments 25 and 26, and the compartment 20. As heretofore stated, the heated air in the compartment is expelled through the openings 29. It is therefore evident that the entire device acts as a radiating surface and effectually warms the air of the room which comes into contact therewith. In reality, this device heats the air of the room by means of the burner pipe 10 and also heats the air by means of the radiating surfaces afforded by the pipes 17 and

18, the compartments 25 and 26, and the compartment 20. As clearly shown in Figures 3 and 4, the under side of the compartment 20 lies in substantially the same plane as the portion 19. The under side of the compartment 20 and the portion 19 therefore provide an air passage which has the walls thereof heated by the heated air passing through the device. As will be seen from Figure 3, the air of the room will enter from the rear of the device and will flow above and below the pipes 17 and 18 and will flow from the device through the front sides thereof.

From the foregoing it will be observed that I have provided a device in which air is caused to circulate on all sides of the members thereof. Air flowing through the radiating pipes will be effectually dried and will be expelled through the openings 29 in a dried state so that when it comes into contact with mirrors or the like, it will not cause the moisture to be formed thereon. Less quantity of gas is required to heat a given sized room with this device than is possible with a device in which the heated air is not first circulated through a series of radiating pipes. As heretofore stated, the device is simple in construction and is durable.

I claim:

A gas heater comprising two side walls, having openings therein, a heat retaining hood disposed between said walls, legs for supporting said walls, a rear wall extending from the bottom of said side walls and terminating adjacent to the hood, a curved deflector plate extending from the lower front side of said side walls and terminating adjacent to said hood, said plate and rear wall forming an air passage extending from the bottom of the heater to the hood, a gas pipe extending between said side walls and parallel with the upper inner end of said plate, a heat retaining chamber disposed above said hood and between said side walls, two pipes disposed in the transverse air passage formed by the hood and chamber, and having their ends secured to the side walls so as to be aligned with the openings in the side walls, stub pipes communicating with the centers of said first named pipes and with the heat retaining chamber, and side heat retaining and conducting compartments carried by said side walls and covering the openings in said side walls, said side walls having other openings placing said side compartments in communication with said hood, with said first named pipes, and with said heat retaining chamber, whereby the heat will take a circuitous path through said heater, said first named chamber having gas outlet openings therein.

CONSTANT VAN SANTVOORT.
